DATA TERMINAL

Dan Nelson and John C. Hutton, Los Angeles, Calif.,
assignors to TRW Data Systems, Inc., Torrance, Calif.

Filed Oct. 21, 1970, Ser. No. 25,569

Term of patent 14 years

Int. Cl. D14—02

U.S. Cl. D26—5

Fig. 1.

Fig. 2.

Fig. 3.

Fig. 4.

Fig. 5.

Fig. 6.

FIG. 1 is a front perspective view of a data terminal showing our new design;

FIG. 2 is a left side view;

FIG. 3 is a top view;

FIG. 4 is a bottom view;

FIG. 5 is a right side elevational view thereof partially broken away and in section to better show the inner details;

FIG. 6 is a back view.

We claim:

The ornamental design for a data terminal, substantially as shown and described.
